RUSSELL C. JONES, OF BRONXVILLE, NEW YORK, ASSIGNOR TO THE GRISCOM-RUSSELL COMPANY, OF NEW YORK, N. Y., A CORPORATION OF DELAWARE.

MULTISTAGE OPEN HEATER.

Original application filed July 28, 1924, Serial No. 728,654. Divided and this application filed March 17, 1927. Serial No. 176,068.

The present invention relates to a steam generating system and has to do particularly with the preliminary heating of feed water on its way to the boilers.

5 The auxiliary apparatus and other steam utilizing devices of a power generating plant invariably furnish a considerable quantity of relatively low pressure steam which must be utilized in the system in order to avoid 10 heat losses. This quantity of steam is usually accommodated by passing it into heat transferring relation with the boiler feed water, thus imparting to the feed water before it enters the boiler heat which would be lost 15 if the heating fluid were discharged to waste.

Modern steam power plant practice tends toward the use in the heating of boiler feed water of both exhaust steam from the various apparatus of the plant and steam withdrawn 20 or "bled" at different pressures from various stages of the plant turbine. According to the common prevailing practice, each of the different sources of steam is passed independently into heat exchanging relation with the 25 boiler feed water. The boiler feed water is passed into heat transferring relation with the respective sources of heating steam in the order of their ascending pressures and temperatures, that is, the feed water first receives heat from the source of steam at the 30 lowest pressure and is successively treated by the other sources of steam at successively higher pressures. Each operation of transferring heat between the heating steam and 35 the boiler feed water is conducted as an independent operation in a separate surface type heat exchanger provided for the purpose.

It is an object of this invention to provide 40 a heater for preheating the boiler feed water which is adapted to receive steam from the plant turbine, or other sources, at different pressures and utilize to advantage the available heat of such steam, yet which involves but a single unitary apparatus possessing the distinct advantages of moderate initial cost, 45 minimum space requirements, notable operating efficiency and convenience of operation. In steam generating systems of the type referred to the supply of boiler feed water

commonly consists of low temperature turbine condensate together with whatever water from the evaporators is necessary to supply the required make-up of the system. The heating steam is commonly exhaust steam from steam engines or steam "bled" from one 50 or more stages of a turbine. Due to the fact that neither the boiler feed water nor the supply of heating fluid contains objectionable impurities, it is permissible to mix these fluids and the present invention contemplates 55 a heat exchange between the respective fluids accomplished by actually intermixing the fluids and thus effecting the heat transfer by direct contact of the fluids. The invention 60 contemplates the provision of a plurality of compartments in the open heater. The heating fluids from the several sources are admitted to the respective compartments at their 65 respective pressures and suitable provision is made for passing the boiler feed water 70 through the respective compartments in series relation. The fluid which is pumped from each compartment to the next succeeding compartment consists of the fluid which 75 was initially admitted to the compartment and in addition the condensate produced by the heating steam which was admitted to that compartment and which was condensed by reason of its contact with the cold feed 80 water.

It is an object of the invention to arrange the various chambers or compartments in which the heat transfer takes place in such fashion that the apparatus has a marked flexibility of design, thus adapting it for incorporation into whatever space is available, and in such fashion that transfer of fluid from one chamber to the next may be conveniently and effectively accomplished. In carrying 85 out this idea, the compartments are mounted in vertical super-position, so that the number of compartments is varied by varying the height of the apparatus.

It is a still further object of the invention to provide a multi-stage open heater of the 90 class referred to of such construction that danger of water from the heater backing up into the turbine or other apparatus where it

would cause damage is effectively avoided. To this end the liquid in each of the heat transferring chambers is introduced at substantially the pressure of the incoming heating steam. As a further precaution, one embodiment of the invention contemplates an overflow control adapted to discharge water from each chamber into the next lower chamber in case an excessive amount of liquid accumulates.

I have, by way of example, illustrated in the accompanying drawings an apparatus embodying my invention. In said drawings:

Fig. 1 is an elevation of one embodiment of the improved heating apparatus;

Fig. 2 is an elevation of a further modification; and

Fig. 3 is a fragmentary view of portions of two adjoining compartments illustrating a modified arrangement.

Referring now to Fig. 1 of the accompanying drawings, the apparatus here shown consists of three compartments C, D and E. Low pressure steam is admitted through the inlet 5 to the compartment E while feed water is supplied to that compartment through the line 6 having in it a float controlled valve 7 operating to maintain a substantially constant liquid level in compartment E. A perforated distributing plate 8, having side walls 9 which extend upwardly to the top of compartment E, so as to enclose a space above the plate which is separated from the rest of the compartment, is provided to receive the liquid entering through the pipe 6 and distributed it within the shell. The water passing through the perforations of plate 8 falls in a continuous shower into the body of liquid at the bottom of the shell, and in this way ample contact is afforded between the liquid and the incoming steam.

A vent pipe 10 opens just beneath the bottom of the perforated plate 8 in the center of the cylindrical shower for the purpose of effecting the discharge of uncondensable gases. It will be noted that in this type of structure deaeration of the feed water may readily be accomplished without heat loss and without providing any special deaerating apparatus. The temperature to which the water is raised in the boiler feed heater serves to effectively expel the injurious gases contained in the water, and the boiler feed as it leaves the heater is fit for use directly in the boilers without further deaeration.

The compartments C and D are provided with steam inlets, feed water inlets and air vents in the same fashion as is compartment E. A pump 11 is provided for withdrawing the partially heated water from the bottom of compartment E and transferring it through line 12 into compartment D. The pump increases the pressure on the water to substantially the pressure of the heating steam which is supplied to chamber D. A second pump 13

withdraws water from chamber D and passes it through line 14 into chamber C. The pumps 11 and 13 are preferably mounted at the base of the heater and are operated by a small turbine or motor 15 provided for that purpose. With this arrangement, the pump 13 which delivers water to the highest pressure compartment C also has a higher head at its suction side than does pump 11 which delivers to the intermediate chamber D. It is of advantage to have the relative arrangement of pumps and compartments such that the head at the suction side of each pump is the greater for those pumps where the temperature of the water handled is greater.

In the modified form of apparatus shown in Fig. 2 the transfer of liquid from one compartment to the other is accomplished by manometer or U-tube connections between adjacent compartments. To facilitate the transfer of the liquid by this method, the highest pressure compartment C is at the bottom instead of being at the top, hence the highest pressure steam is introduced at the bottom compartment of the apparatus through line 5^a, and the lowest pressure steam is admitted to the uppermost compartment E. The coldest feed water which is to be heated enters the uppermost compartment through the line 6^a where it is brought first into contact with the lowest pressure steam. The liquid flows from each compartment to the next lower compartment under the influence of gravity through the U-tubes 16 and 17. It will be understood that the water is heated progressively by contact first with the coolest steam, then with higher pressure steam, and subsequently with still higher pressure steam just as was the case with the apparatus of Fig. 1. The heated feed water is discharged from the lowermost compartment C.

The U-tubes 16 and 17 are of such length that the difference in pressure between the two ends of the U-tube (for instance the difference in pressure between the compartments E and D for the U-tube 16) will not cause the water in the U-tube to blow through the tube. This arrangement has its principal value in cases where a relatively small pressure difference exists between the respective compartments. In cases where a considerable pressure difference between compartments exists, the U-tube might have to be of such a length as to be practically prohibitive in order to prevent fluid from blowing through from the higher pressure compartment to the lower pressure compartment. Where moderate pressure differences exist between the steam sources, however, the external pipe connections forming the U-tubes may be readily varied so as to provide U-tubes of appropriate lengths to suit the pressure conditions. Also, if the pressure difference between compartments E and D, for example, is greater than the pressure difference be-

tween compartments D and C, the lengths of the legs of the U-tubes 16 can be readily made longer or shorter than those of the U-tubes 17.

Now referring particularly to Fig. 3 of the accompanying drawings, there is here illustrated a steam trap 18 which is placed in a line leading from the higher pressure chamber indicated by reference character F to the lower pressure chamber indicated at G. The trap 18 is so constructed that it permits water to pass readily from chamber F to chamber G but prevents the passage of steam between these compartments. This arrangement constitutes an overflow device which serves to discharge liquid from one compartment into the next lower compartment in case an excess of water accumulates in the upper compartment. A partition 19 is provided in the chamber F and as long as the water level remains below the top of the partition, no discharge through trap 18 occurs. Upon accumulation of the water in chamber F to such depth that it overflows the partition 19, a discharge through the trap into the compartment G takes place. This arrangement prevents accumulation of excess water in any compartment. The trap on the lowest pressure compartment discharges to atmosphere. The device substantially eliminates danger of water backing up in any compartment until it fills up the steam connections leading to the compartment with resulting danger to the apparatus from which the steam issues.

While preferred embodiments of my apparatus have been illustrated and described above, certain structural changes may be made and certain variations in the steam generating system may be effected. For instance, the heater of the present application accomplishes a considerable amount of deaeration of the boiler feed water, but the heater may readily be employed in combination with any of the different types of deaerators at present in use. While the heating steam employed is ordinarily free from impurities, suitable provision may be made for separating oil from the steam or water from low pressure steam before admission to the heater if desired. Other changes may be made within the scope of the appended claims.

This application is a division of my pending application, Serial No. 728,654, filed July 28, 1924.

I claim:

1. In a steam generating system, a heater for heating purified boiler feed water comprising a plurality of compartments arranged one above the other, means for supplying heating steam at different pressures to the said respective compartments, the steam at the lowest pressure being admitted to the lowest compartment, means for passing boiler feed water successively through said compartments, the feed water in each compartment mixing with the heating steam admitted to said compartment.

ment, said means comprising a plurality of pumps arranged at the base of the heater, each transferring liquid from one compartment to the next higher compartment whereby the pumps handling the highest temperature water have the highest heads at the suction sides of the pumps.

2. In a steam generating system, a heater for heating purified boiler feed water comprising a plurality of compartments arranged one above the other, means for supplying heating steam at different pressures to the said respective compartments, the steam at the lowest pressure being admitted to the lowest compartment, means for passing boiler feed water successively through said compartments, the feed water in each compartment mixing with the heating steam admitted to said compartment, said means comprising a plurality of pumps, each transferring liquid from one compartment to the next higher compartment whereby the pumps handling the highest temperature water have the highest heads at the suction sides of the pump.

3. In a steam generating system, a heater for heating boiler feed water, comprising a plurality of compartments arranged one above the other, means for supplying heating steam at progressively higher pressures to said respective compartments, means for passing boiler feed water successively through said compartments, said means comprising series-flow external pipes arranged between the adjacent compartments which are at progressively higher pressures, said pipes including means therein for increasing the pressure on the boiler feed water to substantially that of the higher pressure of the next adjacent compartment.

4. In a steam generating system, a heater for heating purified boiler feed water comprising a plurality of compartments arranged one above the other, means for supplying heating steam at progressively higher pressures to said respective compartments, the steam at the lowest pressure being admitted to the lowest compartment, means for passing boiler feed water successively through said compartments, the feed water in each compartment mixing with the heating steam admitted to said compartment, said means comprising series-flow external pipes arranged between adjacent compartments which are at progressively higher pressures, and means therein for increasing the pressure on the boiler feed water to substantially that of the higher pressure of the next adjacent compartment.

5. In a steam generating system, a heater for heating purified boiler feed water comprising a plurality of compartments arranged one above the other, means for supplying heating steam at different pressures to the said respective compartments, the steam at the lowest pressure being admitted to the

lowest compartment, means for passing boiler feed water successively through said compartments, the feed water in each compartment mixing with the heating steam admitted to said compartment, said means comprising a series-flow external pipe arranged between two adjacent compartments which are at

progressively higher pressures, and means therein for increasing the pressure on the boiler feed water to substantially that of the higher pressure of the next adjacent compartment.

In testimony whereof I affix my signature.
RUSSELL C. JONES.
